BURIAL CASKET.

Patented Sept. 29, 1885.

No. 16,293.

UNITED STATES PATENT OFFICE.

JOHN EINSFIELD, OF ONEIDA, NEW YORK.

DESIGN FOR A BURIAL-CASKET.

SPECIFICATION forming part of Design No. 16,293, dated September 29, 1885.

Application filed June 30, 1885. Term of patent 14 years.

To all whom it may concern:

Be it known that I, JOHN EINSFIELD, of Oneida, in the county of Madison, in the State of New York, have invented a new Design for 5 Burial-Caskets, of which the following, taken in connection with the accompanying engraving, is a full, clear, and exact description.

My design consists of the ornamental moldings a, extending along the four sides of the 10 rhomboidal panels A on the exterior of the casket, and the ornamental corner-pieces B at the outside of the oblique ends of the rhomboids. Said moldings I embellish by oblique 15 corrugations or ribs, so as to cause it to present the appearance of the longitudinal section of a rope, as shown, and the corner-pieces B are of right-angle triangular form or fan shape, with leaves b b radiating from the right angle of said corner-pieces.

20 What I claim is—

1. The design for the exterior of burial-caskets, consisting of the rhomboidal panel A, surrounded by the molding a, and the ornamental corner-pieces B outside of the oblique end of the rhomboid, substantially as described 25 and shown.

2. The design for the exterior of burial-caskets, consisting of the molding a, corrugated or ribbed obliquely and extending along the four sides of the rhomboidal panels A, and the 30 ornamental corner-pieces B at the ends of said panels, substantially as shown.

3. The design for the exterior of burial-caskets, consisting of the molding a, extending along the four sides of the rhomboidal panels 35 A, and the triangular corner-pieces B, having radial leaves b b, substantially as described and shown.

In testimony whereof I have hereunto signed my name and affixed my seal, in the presence 40 of two attesting witnesses, at Oneida, in the county of Madison, in the State of New York, this 24th day of June, 1885.
